[57] CLAIM

The ornamental design for a sunglass holder, as shown and described.

DESCRIPTION

FIG. 1 is a perspective view of a sunglass holder showing my new design;

FIG. 2 is a front elevational view thereof, the rear elevational view being the same;

FIG. 3 is a side elevational view thereof, the opposite side being the same;

FIG. 4 is a top plan view thereof; and

FIG. 5 is a bottom plan view thereof.
